(57) CLAIM

The ornamental design for an edging extrusion, as shown and described.

DESCRIPTION

FIG. 1 is a perspective view of the edging extrusion of my invention with the extrusion divided by break lines; FIG. 2 is a right hand side view, the left side view being the reverse of the view shown;

FIG. 3 is a front view of the edging extrusion of FIG. 1 with the extrusion divided by break lines; and,

FIG. 4 is a top plan view of the edging extrusion of FIG. 1 with the extrusion divided by break lines.

The break lines indicate indefinite length.
